UNITED STATES PATENT OFFICE.

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT.

CLOTH-WINDING MACHINE.

Application filed April 2, 1925. Serial No. 20,106.

To all whom it may concern:

Be it known that I, CHARLES G. RICHARDSON, a citizen of the United States, and resident of Springfield, in the county of Wind- 5 sor and State of Vermont, have invented certain new and useful Improvements in Cloth-Winding Machines, of which the following is a specification.

This invention relates to the art of cloth 10 winding, and particularly to the winding of commercial lengths of cloth or fabric upon a core-piece or winding board in order to package the cloth in the form of a flat bolt.

The cloth winding machines that are used 15 for thus packaging the cloth into bolts are well known in the art and, therefore, need not be explained in detail. Essentially they comprise two oppositely aligned board-supporting heads or chucks which are rotated in 20 unison to wind the cloth on the interposed winding board. As the cloth is kept under tension, during this winding operation, the core-board is subjected to considerable strain so that unless the board be of good quality 25 and weight it is likely to buckle or break, in either case producing imperfect packaging of the cloth. It has been proposed to use a metal stiffening plate as a permanent part of the winding machine to reinforce and support the core-board to prevent such buckling, 30 but as the operator is obliged to handle this stiffening plate a great many times a day, the excessive weight of the stiffening plates heretofore used has been a severe tax on the 35 operator and has tended to slow up his work because of fatigue.

It is the object of the present invention to produce a stiffening element for cloth-winding machines of the type above referred to 40 that shall afford a full adequate reinforcement for the thinnest and most flimsy core-boards used, while at the same time keeping the construction so light as to greatly lighten the labors of the winding-machine operator. A further object of the invention is to afford 45 full or complete support for the core-board and for the cloth that is being wound around the same.

To this end the invention comprises a hollow stiffening element of plano-convex cross section presenting a flat face affording support for the core-board, and also affording complete support for the cloth being wound around the core-board so as to insure perfect 50 winding free from wrinkling, while at the

same time a very stiff and a very light construction is obtained. To further increase the stiffness, without materially adding to the weight of the reinforcing or stiffening element particularly in cases where winding- 60 boards are used for wide bolts, I interpose spacing devices between the two members of the stiffening element to prevent any possibility of collapse or buckling. These and other features of the invention will be particularly described in the following specification and will be defined in the claims here- 65 to annexed.

In the accompanying drawings I have shown a simple, cheap and convenient embodiment of the principles of this invention, 70 in which:

Figure 1 is a plan view of the stiffening element mounted in the opposed heads or chucks of a cloth-winding machine, the re- 75 mainder of the machine being omitted.

Figure 2 is a central longitudinal section of the stiffening element held in the opposed chucks.

Figure 3 is a cross-sectional view of said 80 stiffening board on an enlarged scale, showing the spacing devices or struts interiorly disposed therein.

The stiffening element here is shown applied to two opposed rotary chucks of well-known construction. One of said chucks is usually hinged to permit the downward or lateral swinging of the wound bolt of cloth after the opposite end has been dis-engaged 85 from its supporting chuck. 90

The hinged chuck, in this case, comprises a trunnion sleeve 10 secured to a short stub shaft 9 by which it is rotated, and having on its opposite sides trunnions 10^a, which form a pivotal support for the forked clamping head which is made in the form of a yoke whose two outwardly extending arms 12^a are pivotally supported upon the trunnions 10^a, and whose body portion comprises transverse spaced jaws 12 between which is inserted the adjacent end portion of the stiffening element or truss 20, and are held in such inserted position by means of a cotter pin or equivalent device 13, which can be easily removed for inserting different 100 sizes of stiffening elements. A spacing member 14 is secured in the hollow end portion of the truss 20 and is perforated or bored to receive the pivotal connecting pin 13 and thus serves also as a bearing member 105 110

so as to avoid bringing the whole longitudinal stress of the truss upon the thin edges of the truss plates through which it is preferably inserted.

5 The opposite chuck comprises a head 16 with oppositely projecting wings or plates 16^a and movable clamping jaws 17 which are clamped against the adjacent end portion of the inserted stiffening element by means of clamping nuts 17^a.

The stiffening element itself, according to the form illustrated in the drawings, comprises two sheet metal plates 21 and 22, one of which is flat presenting a plane surface 15 affording full contact with the core-board 25 to reinforce or support every portion of it, while the opposed sheet metal plate 21 is transversely bored to form an exterior convex surface which, nevertheless, affords complete 20 plate contact and support for the cloth passing around that face, thereby avoiding wrinkling. The two plates 21 and 22 are rigidly secured together along their sides or longitudinal edges in any suitable manner, as by riveting, welding or the like, so that there is produced a very stiff, light, hollow truss affording full support both for the cloth and for the core-board.

A spacing member 14 is inserted between the separated ends of this reinforcing element to occupy the medial portion of the end attached to the hinged chuck. At the opposite end, that is the end that is released from the chuck to permit removal of the wound bolt, the plate 21 is flattened to lie in parallelism with the adjacent end portion of the plate 22 so as to reduce the thickness of the stiffening element at the end from which the cloth bolt is removed, and also afford a proper shape for firm clamping engagement 40 between the jaws 16 and 17 of the releasing chuck.

To further stiffen the structure I introduce along the medial line a series of short 45 spacing devices or studs 23, particularly where the stiffening element is made of extra length for wide bolts.

In practice, the core-board or bolt-board is placed against the flat face of the stiffening element 20 so as to lie between the projecting ledges formed at each end by the jaw 12 and the jaws 17, and is held in place by simply wrapping the initial end of the cloth around the assembled core-board and 50 stiffening element for one or two turns, after which the machine is started in operation to complete the winding of the bolt. To remove the cloth-board the clamping nuts 17^a are released sufficiently to allow the stiffening element to be swung edgewise out from 55 between the clamping jaws 16 and 17, which movement is permitted by means of the pivotal connection afforded by means of the pivot or fulcral pin 13, carried by the hinged chuck and passing through aligned aper-

tures in the jaws 12, the plates 21, 22 and the intermediate spacing member 14. With the flat end of the stiffening element disengaged from its supporting clamping chuck, the cloth-bolt with its core-board may be readily slipped off from the stiffening element which can then be re-inserted and clamped to its supporting chuck 16. The holding jaws 12 should snugly embrace the fulcral end of the stiffening member but not with sufficient grip or friction to prevent the swinging of the stiffening element to open position to permit the removal of the cloth-bolt.

It will, therefore, be seen that this truss element not only provides a full supporting surface in complete contact with the core-board on one side and the cloth on the other side when a core-board is used, but it is also capable of forming the whole support or reinforcement for the cloth being wound when it is desired to package the cloth without any interior core-board.

What I claim is:

1. In a cloth-winding machine, the combination with rotatable supporting chucks, of a hollow rigid truss member of plano-convex cross-section having one end pivotally connected with one of said chucks for rotative support and having its opposite end detachably secured to the other chuck, thereby providing a reinforcement affording on its plane side complete support for the subtending area of one side of a core-board and on its convex side affording complete supporting contact with the subtending area of the cloth.

2. A reinforcing element for a cloth-winding machine embracing in its construction two sheet metal plates firmly secured together along their side edges, one of said plates being transversely bowed to present an exterior convex cloth-supporting surface, the other plate being flat to present a plane surface to a core-board placed against it and afford full support therefor, substantially as described.

3. A reinforcing element for a cloth-winding machine embracing two sheet metal plates secured rigidly together at their side edges, one of said plates being transversely bowed, the other plate being flat, a spacing member interposed between the plates at one end, said plates being apertured at that end for the reception of a fulcral connecting pin, substantially as described.

4. A reinforcing element for a cloth-winding machine embracing a flat plate and a transversely bowed plate rigidly secured together at their side edges to form a hollow truss, said plates being spaced apart at one end and adapted to receive retaining members for connecting them with a supporting head, the other ends of said plate being secured together in parallelism for insertion

between clamping jaws of another chuck, substantially as described.

5. A reinforcing element for a cloth-winding machine embracing a pair of sheet metal plates rigidly and permanently secured together to form a hollow plano-convex truss, said plates being spaced apart along a medial longitudinal line, and spacing means secured between said plates along 10 said medial line thereby affording a flat exterior surface for supporting an externally disposed core-board on one side and presenting on the other side a convex cloth-supporting surface, substantially as described.

15. 6. In a cloth-winding machine, the com-

bination with two aligned rotatable chucks, of an inter-connecting truss member comprising two sheet metal plates rigidly secured together and rigidly spaced apart along a medial longitudinal line, a spacing 20 and bearing member secured between the spaced portions of said plates at one end, and a connecting pin inserted through said spacing member to form a pivotal connection with the adjacent chuck, substantially 25 as described.

In witness whereof, I have subscribed the above specification.

CHARLES G. RICHARDSON.
